UNITED STATES PATENT OFFICE

96,054

DESIGN FOR A CRAVAT HOLDER

Joseph O. Pollack, Chicago, Ill.

Application April 1, 1935, Serial No. 56,140

Term of patent 7 years

To all whom it may concern:

Be it known that I, Joseph O. Pollack, a citizen of the United States, residing at Chicago, in the county of Cook and State of Illinois, have invented a new, original, and ornamental Design for Cravat Holder, of which the following is a specification, reference being had to the accompanying drawing, forming a part thereof.

Fig. 1 is an elevational view of a cravat holder showing my new design as comprising a rigid body member shown in Fig. 1 and a pendant flexible member; and

Fig. 2 is an end view of the rigid body member.

I claim:

The ornamental design for a cravat holder, as shown and described.

JOSEPH O. POLLACK.
